UNITED STATES PATENT OFFICE.

FREDERIC ECAUBERT, OF BROOKLYN, NEW YORK.

WATCHCASE-BACK.

1,282,396.

Specification of Letters Patent.

Patented Oct. 22, 1918.

Application filed December 13, 1913. Serial No. 806,488.

To all whom it may concern:

Be it known that I, FREDERIC ECAUBERT, a citizen of the United States, residing in the borough of Brooklyn, city of New York, 5 in the county of Kings and State of New York, have invented certain new and useful Improvements in Watchcase-Backs, of which the following is a full and clear specification.

10 My invention relates to watch case backs, bezels, and the like, and to the method and apparatus for producing the same. The invention primarily concerns the production of watch case backs or bezels having internal 15 threads for securing them to the watch case center; but the general principles of the invention are capable of wider application.

The present invention contemplates certain improvements in the threading of the 20 watch case back or bezel, a new and improved method of producing the back or bezel and an improved die construction. In this application I claim only the watch case back or bezel or the like, and reserve the 25 subject matter of the method and apparatus for a divisional application.

In the prior manufacture of threaded backs or bezels for watch cases the threading has had the disadvantage of being incomplete at the last or inner turn, due to the necessity of withdrawing the threading tool to avoid running into the metal at the base of the thread. Also in the manufacture 30 of a die for producing the threads in the back or bezel, the thread has been imperfect at the base of the die thread for this same reason. The thread does not terminate in a circle and the seat of the back or bezel upon the watch case center has consequently been 35 defective. According to my invention the thread in the watch case back or bezel is produced by means of a die on which the threading is formed in such manner that the bevel of the last turn of the thread is 40 maintained right up to the termination of the thread and the threads terminate in a circle or conical surface, whereby the seating and closure of the back or bezel upon the center are more perfect. In the production 45 of the thread die I employ a follower which is applied to the thread preliminarily cut on the die, and forced down to complete the formation of a beveled thread straight through to the termination of the thread, 50 and to provide a circular or conical surface at the base of the thread. This die when

employed in a press for forming the watch case back or bezel thus makes a perfectly beveled thread and conical seating surface. In order that others may be able to practice 60 the invention I shall describe the method and apparatus by which a watch case back can be produced.

The principles of the invention are illustrated by way of example in the accompanying drawings in which—

Figure 1 is a vertical section of the die press in which the watch case back or bezel may be produced;

Fig. 2 is a transverse section of a portion 70 of the watch case back produced thereby;

Figs. 3 and 4 are detail views, partly in section, showing successive steps of the work piece or blank;

Fig. 5 is a detail sectional elevation of a 75 pressure control for the secondary movement of the die press;

Fig. 6 is a perspective view of the threading die and the follower used in the completion 80 of the thread thereon;

Fig. 7 is a similar view of the same with the follower in section;

Fig. 8 is a perspective view of the threading die with the watch case back shown 85 thereon in section.

Referring more specifically to Fig. 1, 10 is the base, and 11 the primary plunger movable therein as, for example, by hydraulic pressure. The primary plunger 11 is provided with a central chamber for the reception 90 of a secondary plunger which comprises the inner or central plunger member 12, and the outer plunger member or follower 13. The central plunger 12 is provided with a central bore 14 terminating below in a valve 95 chamber 15 in which is disposed a ball valve 16, which is normally pressed upward against its seat by valve spring 17 disposed within the primary plunger 11. The primary plunger is engaged by spring plates 100 18, thereby maintaining a space between the two plungers for the reception of pressure fluid, such as oil. Oil is introduced into this space from time to time as required, through the central bore 14, which forms the oil duct, the ball valve 16 being held away from its seat by a suitable tool inserted through the oil duct. The packing 19 closes off the space below the plunger 13, so as to confine the pressure fluid between the primary and secondary plungers. The follower 13 is adjustably secured to the central plunger 12 110

by means of screws 20, which are fixedly secured in the plunger 12 and pass freely through follower 13. The heads of the screws 20 are disposed within recesses 21 of follower 13 and between the screw heads and the bottom of the recesses 21 are confined the pressure springs 22, which normally maintain the follower seated against the plunger 12.

10 Seated upon the top of central plunger 12 is the male die member 23 which is provided with the threading 24 for forming the inner threaded surface of the watch case back, or the like. The male die member 23 is prevented from turning on central plunger 12 by means of pins 25. Surrounding the male die member 23 is the annular rim die 26 which is seated upon the inner annular shoulder of the follower 13.

15 20 Immediately above the die part described a matrix 27 is supported in clamp 27^a. The center die 28, the rim die 26 and the matrix 27 thus constitute the forming die parts for the watch case back or bezel.

25 The apparatus is designed to work upon a blank or work piece, such as shown in Fig. 3, wherein is represented a blank 28 for a watch case back. This blank 28 is positioned on the center die 23 which is the thread forming die, and the primary plunger 11 is then raised under the influence of hydraulic pressure maintaining the secondary plungers with it, and bringing the center die 23 and blank 28 into firm engagement with the 30 matrix 27. It will be apparent that the matrix 27 may have its forming portion designed to emboss or otherwise ornament the back of the watch case back and in such cases it may be necessary to exert especially high 35 pressure by the center die 23. The fluid spaces between the primary and secondary plungers provides for relative motion between them and where high resistances to the movement of center die 23 is encountered, 40 as in producing an embossed watch case back or bezel, the primary plunger 11 will be forced into direct contact with the bottom of secondary plunger 12, so as to exert the full pressure of the primary plunger 11 directly 45 upon the blank. In any case, whether producing an embossed article or not, the relative movement between plungers 11, and 12 will occur to a greater or less extent and thus force fluid from between the two opposite 50 surfaces of these two plungers and into the annular space beneath the follower plunger 13. This will give rise to relative motion between the two plungers 12 and 13 which up to this point moved together, and cause 55 the follower 13 to force the rim die 26 against the bottom of the rim of blank 28. Under the influence of this pressure the metal of the rim of blank 28 is crowded inward and caused to flow into the thread recess 24 60 of the center or threading die 23, thus pro-

ducing the threading in the watch case back or bezel.

In order to avoid excessive pressure being applied by the rim die 26, which might readily occur in the case of producing an embossed watch case back or bezel at which time all of the fluid beneath plunger 12 may be discharged into the annular space beneath follower 13, I provide a pressure regulator which is illustrated in Fig. 5 of the drawings. The regulator or control member comprises a by-pass 29 formed in the primary plunger 11 and leading from the annular space beneath follower 13 to a piston barrel 30, threaded into the plunger 11, against a packing 31. Link 32 is pivoted in lugs 33 and has pivotally secured to its upper end a bar 34 which has notches 35 for the reception of a weight 36, and operates a piston rod 37, which passes through a gland 38 and packing 39, in the piston barrel 30. The piston 37 works in the barrel 30, and under the influence of weight 36 it prevents the occurrence of excessive pressure in the fluid pressure space beneath follower 13. The illustration of the pressure control, as well as the details of construction of the other parts of the die press, should be regarded only as in the nature of an example, of construction embodying the principles of my invention, as it will be apparent that many alterations of design may be made while still performing the functions involved. In order to maintain automatically the proper quantity of oil beneath the secondary plunger, I may further employ an oil cup 50, which communicates with the pressure fluid space by way of neck 51 and check valve 52.

In Fig. 1 of the drawing I have illustrated a yielding lock for preventing the secondary plunger from being drawn out of the primary plunger by the die 23 becoming jammed in the matrix 27. This device comprises a ring 53 seated on a peripheral annular shoulder 54 of the follower 13 which is held in place against distance pieces 55 by means of a spring 56 confined beneath the head of bolt 57, which is threaded into the primary plunger 11.

The operation of the die press may be summarized as follows: The blank 28 is placed over the center or threading die 23 and the primary plunger 11, with the secondary plungers, then raised to bring the blank 28 within the forming space of matrix 27. Whether the blank is to be embossed or not, the operation of plunger 11 will cause pressure fluid to flow into the annular space beneath follower 13, after the die 23 has attained its limit of movement and thereupon the follower 13 will be raised independently of the plunger 12 and cause the metal of the rim of blank 28 to flow into the thread spaces 24 of die 23, thus forming the thread and at 130

the same time producing the flattened seat portion of the watch case back or bezel. During this operation the pressure control device will prevent the occurrence of excessive pressure, the piston 37 being raised by the increased pressure and thereby increasing the space accessible to the pressure fluid, so as to maintain the normal working pressure. The plunger 11 is then lowered, first relieving the follower 13, which is returned to its seat on plunger 12, and immediately relieving plunger 12, which is freed from plunger 11 by the spring plates 18, as the pressure fluid is returned to the space between plungers 11 and 12. The watch case back or bezel remains fixed on threading die 23 from which it may be unscrewed and removed, the pins 25 facilitating the unscrewing of the back or bezel by preventing turning of the die 23.

In addition to the general arrangement and operation of the die press, which has now been described, my invention further comprises an improvement in the manufacture and construction of the threading die 23, above described. In cutting a thread upon a cylindrical member, such as die 23, it will be obvious that while the bevel of the thread may be complete at the outer end 45 of the cylinder, the last turn of the thread at the inner end will be beveled on the outer side only or, in other words, the threading will terminate in a surface which is not cylindrical, but has a spiral surface. In the construction of the threading die 23 I provide for the continuance of the bevel up to the termination of the thread and in this way form a circular instead of a spiral base. In other words, the threading produced is perfect, just as would be the case in threading a cylinder straight through from one end to the other, without the interference of metal abutting the threading tool, as it arrives at the end of the cut. This construction is illustrated in Figs. 6, 7 and 8, and is of primary importance to the threading of the watch case back or bezel, as will appear. Referring to Fig. 6 the die 23 is here illustrated with the thread 24 partially turned therein. This threading as completed by the ordinary cutting tool in a lathe terminates in a spiral section or a base which is not at right angles to the axis of the cylinder and hence is not a circle. In order to complete the bevel of the last turn of thread and cause the thread to terminate in a circle or conical surface, as distinguished from a spiral surface, I employ a finishing die or cutter 40, which has the thread cutting surfaces 41 continuing straight through with perfect bevel from beginning to end, and terminating in a conical surface 42, which

leads to an enlargement 43 of the inner recesses. This finishing die is threaded on to the imperfect thread produced in the lathe, and forced through the metal beyond the incomplete thread to complete the formation of the thread on the die 23. This finishing die thus in effect cuts a remainder or terminal section of the thread and forms on the die 23 a circular or conical surface 44, corresponding with surface 42 of the finishing die 40. The threads produced on die 23 thus continue with perfect bevel straight through to the circular or conical surface 44.

The feature just described provides for a perfect or complete thread terminating in a transverse plane at the web portion in the finished watch case back or bezel. As illustrated in Fig. 8, the blank 28 receives from the die 23, a perfect bevel thread at the inner end 45 of the watch case back thread, which can not be produced by the usual lathe operation, and its outer end 46 is likewise perfectly beveled and terminates in a conical surface. This construction is illustrated in Fig. 2 on an enlarged scale. The application of the watch case back to the center of the watch case is greatly facilitated by the conical surface 46, and the complete bevel of the threading provides a more perfect attachment of the back to the center, resulting in a dust proof seating of the back or bezel upon the center, so that the lines of demarcation between these parts of the watch case are practically invisible, thus enhancing the appearance and effectiveness of the watch case.

I claim:

1. A watch case back or the like, comprising side and web portions, the side portion having internal threading beveled on both sides and terminating in a single transverse plane at the web portion, and a counter-sunk surface intersecting with the thread at the entrance.

2. A watch back or bezel having its edge thickened and compressed into substantially solid form and with the inner face of the thickened portion in cylindrical relation to the axis of the article and a screw thread swaged in said face, substantially as described.

3. A watch back or bezel having its edge thickened and compressed into substantially solid form and with the inner face of the thickened portion screw-threaded in cylindrical relation to the axis of the article.

FREDERIC ECAUBERT.
